(57) **CLAIM**

The ornamental design for a stick on body pocket, as shown.

DESCRIPTION

FIG. 1 is a perspective view of a stick on body pocket, showing the new design in use;

FIG. 2 is a left side elevational view thereof;

FIG. 3 is a right side elevational view thereof;

FIG. 4 is a front perspective view thereof;

FIG. 5 is a top plan view thereof;

FIG. 6 is a bottom plan view thereof;

FIG. 7 is a front plan view thereof; and,

FIG. 8 is a back plan hand front view thereof.

The broken line showing of a human figure and fold lines is included for the purpose of illustrating environment and forms no part of the claimed design.

1 Claim, 3 Drawing Sheets

FIG. 7

FIG. 8
